CLAIM

The ornamental design for an attachment for facial cleansing apparatus, as shown and described.

DESCRIPTION

FIG. 1 is a top perspective view of an attachment for facial cleansing apparatus, showing my new design;

FIG. 2 is a bottom perspective view thereof;

FIG. 3 is a front elevational view thereof; the rear elevational view is a mirror image thereof;

FIG. 4 is a left elevational view thereof;

FIG. 5 is a right elevational view thereof;

FIG. 6 is a top plan view thereof; and,

FIG. 7 is a bottom plan view thereof.

1 Claim, 4 Drawing Sheets
